UNITED STATES PATENT OFFICE.

ANDREW J. WIEGAND, OF BALTIMORE, MARYLAND.

DESIGN FOR A GAS-COCK.

SPECIFICATION forming part of Design No. 32,060, dated January 2, 1900.

Application filed November 18, 1899. Serial No. 737,526. Term of patent 14 years.

To all whom it may concern:

Be it known that I, ANDREW J. WIEGAND, a citizen of the United States, residing at Baltimore, in the State of Maryland, have invented and produced a new and original Design for Gas-Cocks, of which the following is a specification, reference being had to the accompanying drawing, forming part thereof, in which the figure is a side elevation of a gas-cock, showing my new design.

The leading or material feature of my design consists of the design forming the subject-matter of the accompanying illustration.

As shown, the gas-cock is formed with the central cylindrical portion A, surmounted by the upper section B, whose base is of less diameter than the portion A, and such section tapers toward its apex, as shown. The cylindrical portion D is below and of less diameter

than the portion A, and a slender projection E extends from the portion A and is bent at E', so its upper portion extends approximately parallel with the axis of the tapered portion B. A circle is produced at F upon the central cylindrical portion A. A rod G extends from the upper end of the projection E and is surmounted by a relatively broad perforated plate H, arranged laterally to and at an angle to the axis of the tapered section B.

Having described my invention, what I claim, and desire to secure by Letters Patent, is—

The design for a gas-cock, as herein shown and described.

ANDREW J. WIEGAND.
